DESIGN FOR A QUILT

Mary A. Stover and Wallace P. Stover, New York,
N. Y., assignors to Heirloom Needlework Guild,
Inc., New York, N. Y., a corporation of New York

Application November 18, 1944, Serial No. 116,430

Term of patent 14 years

(Cl. D92—2)

To all whom it may concern:

Be it known that we, Mary A. Stover and Wallace P. Stover, both citizens of the United States and both residents of the city of New York, in the Borough of Manhattan, county and State of New York, have invented a new, original, and ornamental Design for a Quilt, of which the following is a specification, reference being had to the accompanying drawing, forming part thereof.

In the drawing, the figure is a top plan view of a quilt showing our new design.

We claim:

The ornamental design for a quilt, substantially as shown.

MARY A. STOVER.
WALLACE P. STOVER.
